J. D. JUDKINS

DISH DRAINER

Filed Nov. 3, 1919

By

Ch. Farren Attorney

UNITED STATES PATENT OFFICE.

JOHN D. JUDKINS, OF SAN DIEGO, CALIFORNIA.

DISH DRAINER.

Application filed November 3, 1919. Serial No. 335,521.

To all whom it may concern:

Be it known that I, JOHN D. JUDKINS, a citizen of the United States, residing at 639 E St., San Diego, county of San Diego, and 5 State of California, have invented a certain new and useful Improvement in Dish Drainers, of which the following is a specification.

An object of the invention is the provision of a dish drainer that may be arranged on a 10 wall or other substantially flat vertical surface in which dishes to be drained may be supported in a substantially vertical position, spaced from each other.

Another object of this invention is to provide a dish rack, in a convenient place to receive and retain said dishes, etc., while 15 being rinsed by a shower of hot water.

With these and other objects in view the present invention consists in the combination 20 and arrangement of parts, as will be hereinafter more fully described, shown in the accompanying drawings, and particularly pointed out in the appended claim, it being understood that changes in the form, 25 proportion, size, materials used, and minor details may be made within the scope of the claim without departing from the spirit or sacrificing any of the advantages of the invention.

30 In the drawings, Fig. 1 shows in plan a lavatory with the dry-rack in position.

Fig. 2 is a front elevation thereof.

Fig. 3 is a vertical sectional view on the line 3—3, Fig. 1, showing the location of 35 the cut-off valve, the over-flow outlet and showing the dry-rack 4 in position.

Referring in detail to the drawings, the letter A designates generally a sanitary bowl or vessel preferably made of cast iron, the 40 interior surfaces thereof being coated with white enamel, the bowl being provided with a back B extending upwardly therefrom a considerable distance. The usual hot and cold water spigots C may be arranged above 45 the upper edge of the back and adapted to deliver water into the bowl. A cutoff valve 1 is arranged in the outlet 2 of the bowl, the outlet pipe being covered by a strainer 3 to prevent coarse materials from entering the 50 pipe and clogging the cutoff. An overflow pipe 4 is connected at its lower end to the drain or waste-pipe, and communicates with the bowl near the top as at 5. The drying

rack, which is employed for rinsing and drying dishes, consists of a wire basket 6 supported above the basin or sink by suitable supporting mechanism. As shown, I-bolts 7 are secured in the back B of the basin and are adapted to receive hooks 8 carried by the basket. The front 10 of the basket diverges upwardly and outwardly (see Figure 3) and is formed of relatively close longitudinal wires 11 and spaced transverse wires 12. These spaced transverse wires extend across the bottom of the basket as shown in Figure 1 of the drawings. The ends of the basket also diverge upwardly and outwardly and are formed of wire mesh. As shown, the longitudinal wires 11 of the front are continued to form the longitudinal wires of the 60 ends and are connected by relatively close transverse wires 13. As shown in Figure 1 of the drawings, the back edges of the ends and bottom are arranged in substantially the same vertical plane whereby the drainer may 65 be arranged in front of a substantially flat vertical wall and the wall form the back of the drainer.

After the dishes have been washed, they 70 may be arranged in the basket 6, rinsed and then permitted to dry. A suitable amount of clean water may be arranged in the basin, the water line being indicated at 9 in Figures 2 and 3 of the drawings. As shown, the water line is arranged below the bottom 75 of the basket so that the dishes do not extend into the water. The dishes may be sprinkled with clean water from the basin and then permitted to drain.

The spaces between the wires 11 and 12 80 are sufficiently large to permit portions of the dishes to project through them. By inclining the front wall of the basket, the dishes may be supported in substantially 85 vertical planes and slightly spaced from each other, whereby they may be more effectively drained.

Having thus described my invention, what 90 I claim, and desire to secure by Letters Patent, is—

100 A dish drainer comprising a basket of woven wire having a front wall and end walls inclined outwardly toward the top and having a bottom, the bottom and front wall being formed of relatively close longitudinal wires and transverse wires spaced sub- 105

stantially far apart forming relatively long, narrow mesh openings whereby the lower edges of the dishes within the basket may project therethrough, the rear edges of the end walls and bottom being arranged in substantially the same vertical plane, whereby said drainer may be hung against a substan-

tially flat vertical surface, and the surface serve as a back for said drainer.

JOHN D. JUDKINS.

In presence of—

V. J. HOUSTON,
D. L. NOBLE.
